UNITED STATES PATENT OFFICE.

THOMAS J. MOODY, OF PETERSBURG, ILLINOIS, ASSIGNOR OF ONE-THIRD TO
MABURY L. BEAN AND ONE-THIRD TO CLARENCE R. TURNER, BOTH OF
PETERSBURG, ILLINOIS.

BARREL.

1,363,145.

Specification of Letters Patent. Patented Dec. 21, 1920.

Application filed June 15, 1920. Serial No. 389,113.

To all whom it may concern:

Be it known that I, THOMAS J. MOODY, a citizen of the United States, residing at Petersburg, in the county of Menard and 5 State of Illinois, have invented a new and useful Barrel, of which the following is a specification.

This invention relates to knock down barrels, one of its objects being to provide a 10 barrel which can be transported, complete, in a compact form and which can be easily set up for use without requiring the use of any special tool or the services of a skilled mechanic.

15 With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

25 In the accompanying drawings the preferred forms of the invention have been shown.

In said drawings—

30 Figure 1 is an elevation of a barrel having the present improvement combined therewith, a portion being broken away.

Fig. 2 is an elevation of a portion of the barrel showing the parts disconnected.

Fig. 3 is a section on line 3—3, Fig. 2.

35 Fig. 4 is a section on line 4—4, Fig. 2.

Fig. 5 is an elevation of a modified form of fastening device, the barrel staves being shown moved apart.

Fig. 6 is a section on line 6—6, Fig. 5.

40 Referring to the figures by characters of reference 1 designates ordinary barrel staves adapted, when properly assembled and set up, to surround heads one of which has been shown in Fig. 1 and both heads being alike.

45 Each head is preferably formed of an intermediate section 2 and end sections 3, said end sections being hingedly connected, as at 4, to opposite faces respectively of the intermediate section so that the sections can 50 be folded one upon the other.

Hoops 5 are adapted to be slipped onto the ends of the barrel so as to bind the staves onto the heads in the usual manner. A flexible hoop connects the staves at the

center. In the structure shown in Figs. 1 to 55 4 inclusive the sectional hoop is made up of wire links 6 each of which has terminal eyes 7 formed by looping the end portions of a link of wire forming the link. The ends of the wire are coiled or wrapped about the 60 intermediate portion of said wire and form prongs which are adapted to be driven into and clenched within the adjacent stave across which the wire is extended. The clench has been clearly illustrated at 8 in Fig. 4. As 65 each of the wire links has both of its ends clenched in the stave on which the link is mounted it will be obvious that said link is thus firmly secured in place. The eyes on the adjoining links interfit so that the 70 links form a chain or hoop which will flex when the hoops 5 are removed, thus to allow the staves to be laid substantially flat when the barrel is in knock down condition. The terminal eyes formed at the ends of the 75 chain or hoop are enlarged as indicated at 9 and 10 respectively. To one of these eyes, 9, is pivotally connected a tongue 11 suitably secured to one of the end staves of the barrel and having a short bolt or threaded 80 stud 12 extending outwardly therefrom. Another tongue 13 is pivotally connected to the eye 10 and has spaced openings 14 either of which is adapted to receive the bolt or stud 12 which is fastened in place by a nut 85 15 or the like.

It is to be understood that the two tongues 11 and 13 can only be fastened together after the staves of the barrel have been set up for use. The stud 12 is insertible into the 90 most convenient opening 14 and fastened, and when the parts are thus secured the staves will properly contact as shown in Fig. 1. The barrel heads are of course placed in position and the hoops 5 can be 95 driven onto the staves so as to bind them on the heads. To knock down the barrel the tongues 11 and 13 are disconnected from each other and the hoops 5 are removed. Thus the staves can be laid out substantially 100 flat and the heads can be folded and conveniently stored.

Instead of making the flexible hoop out of wires forming links such as described, the hoop can be made of flat metal links 16 fastened to the respective staves by rivets 17 or the like. Each of these links 16 has terminal eyes 18 and mounted in the eyes are

connecting loops or links 19. The strip 16 forming one end of the flexible hoop has a button 20 pivotally mounted thereon and the strip 16 forming the other end of a hoop is not attached to a stave but hangs freely and has a slot 21 therein. Thus when the barrel is set up for use the end strip 16 will lap and the button 20 can be inserted through the slot 21 and then rotated so as to fasten 10 the two end strips together as shown in Figs. 5 and 6.

What is claimed is:

1. In a knock down barrel, a plurality of staves, a link extending transversely of each 15 stave at the center thereof, each link comprising a single link of wire bent to form end eyes and inwardly extending prongs, the prongs of each link being clenched within the stave on which the link is mounted, the eyes 20 on the links of adjoining staves interfitting to form a flexible hoop, a tongue pivotally connected to one eye on one of the links and secured to a stave, another tongue secured to the eye of another link, the two tongues 25 forming the ends of the flexible hoop, and co-

operating means upon the two tongues for fastening them together.

2. In a knock down barrel, a plurality of staves, a link extending transversely of each 30 stave at the center thereof, each link comprising a single link of wire bent to form end eyes and inwardly extending prongs, the prongs of each link being clenched within the stave on which the link is mounted, the eyes on the links of adjoining staves interfitting to form a flexible hoop, a tongue 35 pivotally connected to one eye on one of the links and secured to a stave, another tongue secured to the eye of another link, the two tongues forming the ends of the flexible 40 hoop, and an attaching stud projecting from one of the tongues, there being a plurality of apertures in the other tongue.

In testimony that I claim the foregoing as my own, I have hereto affixed my signature in the presence of two witnesses.

THOMAS J. MOODY.
